UNITED STATES PATENT OFFICE.

LOUIS K. SCOTFORD, OF CHICAGO, ILLINOIS, ASSIGNOR TO THE ORO-TONE COMPANY, OF CHICAGO, ILLINOIS, A CORPORATION OF ILLINOIS.

SOUND BOX.

Application filed July 9, 1921. Serial No. 483,400.

To all whom it may concern:

Be it known that I, LOUIS K. SCOTFORD, a citizen of the United States, residing at Chicago, in the county of Cook and State of Illinois, have invented certain new and useful Improvements in Sound Boxes, of which the following is a specification.

The present invention relates to sound boxes.

10 More particularly, the present invention relates to sound boxes for sound reproducing machines and contemplates a novel method of mounting the diaphragm in a sound box. It has been common practice heretofore, to 15 hold said diaphragm in place by means of an annular ring which, in turn, is held in place by set screws or other holding means.

An object of the present invention is to provide a holding means for a diaphragm in 20 a sound box which is inexpensive to construct and assemble.

A further object is to provide a diaphragm mounting for a sound box which presents a neat appearance.

25 A further object is to provide a method of mounting a diaphragm in a sound box which will be inexpensive and effective.

Further objects will appear as the description proceeds.

30 Referring to the drawings, Figure 1 illustrates a sound box embodying the present invention.

Figure 2 is a sectional view taken along the line 2--2 of Figure 1.

35 Figures 3 and 4 are detail views illustrating the method of practicing the present invention.

The sound box is indicated by the numeral 10. Said sound box has a tone arm connector 40 11 of the usual construction, which is adapted to be connected to the tone arm of a sound reproducing machine. The sound box is provided with an annular flange 12 adapted to receive the diaphragm 13. Said diaphragm 13 is mounted between two annular gaskets 14 and 15, of which gaskets, the one indicated as 14 lies at the bottom of the space provided by the annular flange 12. If preferred, the sound box may be provided with 45 a boss 16 which will lie within the gasket 14 and serve to locate said gasket 14 centrally of the space within the flange 12. The diaphragm 13, together with gaskets 14 and 15, is held in place by means of the bezel 17.

55 The stylus bar 18 will be connected to the

diaphragm 13 and to the needle socket 19 in a manner well understood. In ordinary practice, the sound box 10 will be cast, and in order that the casting may be withdrawn from the mold, the space internally of the 60 flange 12 will be slightly conical, the largest diameter being outermost. This slightly conical conformation is made use of in the practice of the present invention. The bezel 17, before being mounted within the flange 65 12, will be a substantially cylindrical member beaded over on one edge as indicated by the numeral 20. The outer diameter of the cylindrical wall of the bezel 17 should be less than the largest diameter within the annular 70 flange 12 but greater than the least diameter within said flange 12.

In mounting the diaphragm 13 within the sound box, the gasket 14, diaphragm 13 and gasket 15 will be loosely dropped into place 75 and the bezel 17 will be placed within the space provided by the annular flange 12. Pressure will be exerted against the beaded portion of the bezel 17 to swage said bezel into uniformly tight engagement with the 80 inner wall of the flange 12, whereby said bezel 17 will be held securely in place within said flange 12. The parts will be so designed that when the bezel 17 is pressed home, the diaphragm 13 will be held firmly in place between gaskets 14 and 15.

The mounting illustrated and described is inexpensive, is very effective and presents a good appearance.

One embodiment of the present invention 90 has been described in detail. Many modifications will occur to those skilled in the art. It is intended in this patent to cover all such modifications that come within the scope of the invention as defined by the appended 95 claims.

What I claim as new and desire to secure by Letters Patent in the United States, is:

1. The method of mounting a diaphragm, which consists of providing a sound box having a conical recess and a bezel having a cylindrical wall portion of an external diameter small enough to enter said recess but too large to seat in the bottom of said recess, mounting said diaphragm and said bezel in 100 said recess and applying pressure on said bezel to force same into said recess with a swaging action.

2. The method of mounting a diaphragm in a conical recess, which consists in provid-

ing a pair of annular gaskets and providing a bezel having one side beaded over and the other side plain, said plain side having an external diameter small enough to enter said recess but too large to seat readily in the bottom of said recess, mounting said diaphragm with one of said gaskets on each side thereof and said bezel plane side innermost in said recess and forcing said bezel into said recess 10 to a position in which said bezel tightly grips the wall of said recess and in which said gaskets are compressed to grip said diaphragm.

3. In a sound box, means providing a round recess having an internal inwardly tapering wall, a diaphragm mounted in said recess and a bezel for holding said diaphragm in place, said bezel having a beaded edge portion exerting pressure against said diaphragm and another edge portion contacting in swaged condition with said tapering wall. 15 20

Signed at Chicago, Illinois, this 5th day of July, 1921.

LOUIS K. SCOTFORD.
